UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MECHANISM FOR USE IN SHAPING SHOE UPPERS.

1,407,321.

Specification of Letters Patent. Patented Feb. 21, 1922.

Application filed February 2, 1917. Serial No. 146,249.

To all whom it may concern:

Be it known that I, MATTHIAS BROCK, a citizen of the United States, residing at Boston, in the county of Suffolk and State 5 of Massachusetts, have invented certain Improvements in Mechanism for Use in Shaping Shoe Uppers, of which the following description, in connection with the accompanying drawings, is a specification, like referring 10 to characters on the drawings indicating like parts in the several figures.

This invention relates to shoemaking and particularly the shaping of the upper materials including the removal of surplus 15 stock from the margin of such materials.

When, in the earlier development of shoemaking machinery, it was customary to pull over shoes by hand, it was found expedient to prepare the upper for the pulling over 20 and lasting operation by pinking or notching the toe end of the vamp, as explained in a patent granted to myself and E. Woodward, Jan. 21, 1879, No. 211,612, so that when the margin of the vamp was gathered 25 inwardly over the toe of the insole it would lie comparatively smooth and there would not be a surplus of upper material producing a bunch interfering with the proper laying of the outsole. With the introduction of 30 the pulling-over machine, this preparation of the upper was found to be objectionable because it was found difficult to present such a notched edge satisfactorily to the toe pincer of the pulling-over machine, and 35 thereafter the notching of the upper was effected after the pulling-over operation by the use of what is known as the Carter pinking tool built under Patent 591,999, Oct. 19, 1897. An alternative system was to form 40 slits in the upper during the lasting operation, this system being used particularly in connection with the step-by-step lasting machines of the hand method type and permitting the upper to be pleated smoothly 45 enough so that in light shoes it was unnecessary to trim off any stock. More recently the surplus material has been efficiently dealt with in a separate operation following the lasting in which the tread face of the toe 50 portion of the lasted shoe is presented to a rotary cutter which trims or grinds away the surplus material leaving a smooth seat upon which to lay the outsole. In the search for economies in the shoe manufacturing proc-

esses to offset the increase of costs of materials, there has arisen a demand for the elimination of this separate toe grinding or trimming operation with the additional handling of the shoe which it involves, and simultaneously manufacturers are seeking to introduce better standards of lasting. It is an object of this invention to satisfy this demand and to contribute also to improved results in shaping uppers. To this end one important feature of this invention consists 55 in the combination with means to gather the end portion of an upper inwardly over a last or equivalent shoe form and hold it in position to be trimmed, of trimming means constructed and arranged to co-operate in a 60 novel manner with said gathering means to trim off the marginal edge portion of the upper extending round the edge of the shoe beyond the acting edge of the gathering means. This feature of the invention may 65 be advantageously embodied in mechanism comprising the usual toe lasting wipers operated to gather the upper over the insole as described and a cutter suitably shaped with relation to said wipers to trim off the 70 surplus of upper projecting inwardly beyond the wipers, the trimming means herein shown being constructed and arranged to 75 assume an operative position at the rear of the toe end of the shoe and to be operated 80 independently of the wipers. In the illustrated embodiment of the invention the cutter is of the chisel type arranged to operate substantially perpendicularly to the plane 85 of the insole to trim off the marginal edge of 90 the upper held in an inwardly projecting position by the gathering means, although it is within this invention, in some of its aspects, to employ a cutter of any suitable 95 type or shape arranged to operate efficiently for the purpose.

Another feature of this invention consists in a novel construction and arrangement of cutter and co-operating means for severing the marginal edge of the upper, the construction shown comprising a member having an edge contour adapting it to the toe of a shoe, said member being of appropriate thickness to enter between the toe portion of an insole and the overlying portion of the 100 upper material gathered over the shoe bottom, and a cutter adapted to co-operate with said member to sever the surplus stock from 105

the upper. This feature is herein shown as embodied in a relatively stationary plate shaped to be inserted between the insole and the margin of the overwiped upper in combination with a cutter shaped and arranged to co-operate with said plate in effecting a shearing cut.

Other features of the invention consist in a novel construction and arrangement of 10 cutter and means for determining its relation to the shoe for the proper performance of its function, and in various details of construction and combinations of parts, all of which will be more fully understood from 15 the following description of the illustrative embodiment of the invention shown in the accompanying drawings.

Fig. 1 of the drawings is a perspective view showing toe wipers and co-operating 20 upper trimming means in accordance with the illustrative embodiment of the invention.

Fig. 2 is a sectional view through the trimming means showing it in position for use.

25 Fig. 3 is a perspective view of the trimming means.

The toe lasting mechanism may be constructed and arranged substantially as shown in my co-pending application Ser. No. 30 124,187, filed Oct. 6, 1916, upon which Letters Patent No. 1,390,755 were granted on Sept. 13, 1921. A detailed description of the lasting mechanism is not essential here further than to point out that it comprises a toe rest 35 2 upon which the forepart of the shoe is supported, toe embracing wipers 4 connected through a plunger with a hand lever 5 by means of which the wipers are advanced. The wipers are guided by suitable cam tracks 40 to cause them to close when they are advanced and thereby to gather the toe portion of the upper inwardly over the toe of the shoe insole and hold the upper in position for the action of the trimmer in removing 45 the surplus of the upper extending inside of the tacking line and tending to produce a bunch upon the bottom of the lasted shoe.

The illustrated embodiment of the trimming mechanism comprises a bar or stem 50 8 adapted to extend perpendicularly to the plane of the shoe bottom and provided on its lower end with a foot or base member 10 comprising a plate or flange having an edge contour adapting it to the toe of the shoe, 55 said flange being of suitable thickness to be inserted between the face of the insole and the marginal portion of the upper which has been gathered over the toe of the insole by the wipers. Carried and movable endwise 60 on the stem 8 is a sleeve 12 the upper portion of which is formed to adapt it to be grasped by the hand of the operator. The sleeve carries a knife 15 here shown as circular in 65 form and of the chisel type and having an edge contour adapted to co-operate with the

foot or flange 10 in effecting a shearing cut through the upper materials to remove the surplus upper stock. The active shearing edges of the illustrated foot and knife are curved and have a contour that will shear 70 off the surplus stock along a line approximating the contour of the adjacent edge of the sole. The cutter is shown as extending entirely around the sleeve so that in its operation it will entirely disconnect from the upper the trimming or piece of surplus material 75 which it severs from the upper. The cutter 15 is shown as fastened to the sleeve by removable screws permitting its replacement, and movements of the cutter relatively to 80 the stem 8 are limited by means of a cross pin 16 carried by the sleeve and extending through a slot 18 in the stem, thereby insuring against damage to the insole in the cutting operation. A cutter lifting spring 85 20 is located in a recess in the stem and acts upwardly against an adjustable stud 22 carried by the sleeve. The sleeve is enlarged at its upper end to present a head adapted to be engaged by a suitable striking implement 90 such as 25, if desired, to force the knife through thick upper material. If the upper material does not offer too much resistance, the knife can be forced through it by pressure transmitted through that hand of the 95 operator which grasps the sleeve.

A manner of using this invention which has been found satisfactory is to position the shoe upon the toe rest and clamp it by means of the usual hold-down of the lasting machine, and then employ the wipers for shaping the upper around the end of the toe and for then gathering the upper inwardly over the bottom face of the insole. Usually an operator advances and retracts the wipers 100 several times until he has the upper positioned correctly and formed satisfactorily without wrinkles which will show in the surfaces that are exposed to view when the shoe is completed. He then backs the wipers 105 partially off the toe to uncover the tacking line and inserts the foot 10 between the insole and the overwiped upper materials as shown in Fig. 2, positioning the foot so that just the portion of upper which is superfluous 110 will be trimmed off. This, of course, varies in different shoes and the possibility of positioning the cutter for each shoe in accordance with the operator's judgment is advantageous. The foot having been properly located, the operator presses down the cutter into engagement with the upper and if the upper material is thick he strikes the head of the knife carrying sleeve with the tool shown in Fig. 1 to drive the cutter through 115 the stock. The wipers hold the stock in position to be cut and guide the operator in correctly cutting it. The foot 10 and the knife co-operate in making a clear, clean cut 120 entirely through the upper materials without 125 130

injuring the insole. The shape of the cutter insures that the surplus material will be entirely disconnected from the shoe at both sides of the toe.

5 While the invention is shown as employed in connection with the lasting operation, it is of course practicable to use other means than toe lasting wipers for gathering the upper materials over the insole and holding them for the toe trimming operation, and I have also contemplated the use of the toe trimmer on a shoe after the lasting and toe fastening has been completed whether the shoe is held in the lasting machine or otherwise supported for the purpose. As I am now advised the best results are obtained, however, by following the procedure first above outlined and trimming off the surplus upper material after the upper has been shaped to and wiped over the toe and while it is held by the wipers prior to the insertion of the lasting tacks. It will be understood that by the use of this invention the separate toe trimming operation is wholly eliminated, thus saving the factory space and equipment involved in the use of a separate toe trimming machine and that the trimming operation can be effected before the lasting is completed, thereby getting the surplus upper material out of the way of the lasting instrumentalities during the final portion of the lasting operation and prior to the toe tacking operation. This latter is important in that it enables the lasting to be more smoothly effected upon the bottom of the toe, and the removal of the surplus material before the tacking permits the upper to be more compactly tacked to the insole than is practicable before the surplus material has been cut away. There is also the further advantage that the lasted and fastened condition of the toe is not disturbed by a subsequent trimming operation, more or less of such disturbance being inevitable when the upper was trimmed after the lasting and tacking had been completed.

While the invention is herein illustrated and described with reference particularly to trimming off the surplus margin of the upper at the toe end of a shoe, it is not intended thereby to imply any limitation with respect to such features of the invention as are clearly of utility irrespective of the particular portion of the shoe upon which the trimming operation is performed.

Having explained the nature of this invention and described a preferred embodiment thereof, I claim as new and desire to secure by Letters Patent of the United

60 States:—

1. In means for removing surplus upper stock from the toes of shoes, the combination of a member having a curved edge adapting it to the toe of a shoe and a thickness to enter between the toe portion of an insole and

the overlying portion of a shoe upper, and a cutter having a curved edge adapted to co-operate with said member to sever the surplus stock from the upper.

2. In means for removing surplus upper stock from the toes of shoes, the combination of a member having an edge contour approximating that of the toe of a shoe and a thickness to enter between the toe portion of an insole and the overlying portion of a shoe upper, and a cutter guided in co-operative relation to said edge contour to shear off surplus upper on a line determined by the edge contour of said member.

3. In means for removing surplus upper stock from the toes of shoes, the combination of a member having an edge contour adapting it to the toe of a shoe and a thickness to enter between the toe portion of an insole and the overlying portion of a shoe upper, a stem by the aid of which said member may be placed in working position, and a cutter guided for movement longitudinally of said stem to shear the upper along the edge contour of said member.

4. In means for removing surplus upper stock from the toes of shoes, the combination of a member having an edge contour adapting it to the toe of a shoe and a thickness to enter between the toe portion of an insole and the overlying portion of a shoe upper, a stem by the aid of which said member may be placed in working position, a sleeve sliding on said stem and adapted to be grasped by the hand of a workman, a cutter carried by the sleeve to co-operate with the edge of said member, and a spring for holding the cutter normally upraised to facilitate introduction of said member under the portion of upper to be cut.

5. In means for removing surplus upper stock from the toes of shoes, the combination of a stem having a foot to be inserted under the overbent upper at the toe of a shoe, a shear knife guided by the stem to co-operate with the foot in trimming the upper, means for raising the knife, and means adapted to receive motion for impelling the knife toward the foot and through the upper.

6. In means for removing surplus upper stock from the toes of shoes, the combination of a cutting plate having a curved edge approximating the curve at the toe end of a shoe sole, said plate being shaped and arranged to be positioned under the overbent toe portion of a partially lasted upper, and a shearing cutter mounted for movement in relation to said edge to cut the upper on the line of said edge.

7. In means for removing surplus upper stock from the toes of shoes, the combination of a sleeve carrying a toe trimming cutter, and a stem lengthwise of which the sleeve is guided for endwise movement and which is adapted to be engaged with the shoe in-

sole in proximity to the upper to guide the cutter into desired cutting relation to the upper.

8. In means for removing surplus upper stock from the toes of shoes, the combination of a sleeve carrying a toe trimming cutter, and a stem on which the sleeve is guided for endwise movement and which is adapted to be engaged with the shoe insole in proximity to the upper to guide the cutter into desired cutting relation to the upper, said cutter sleeve having a portion shaped to be grasped by the hand of the workman for effecting operation of the cutter.

15 9. In means for removing surplus upper stock from the toes of shoes, the combination of a sleeve carrying a toe trimming cutter, a stem on which the sleeve is guided for endwise movement and which is adapted to be engaged with the shoe insole in proximity to the upper to guide the cutter into desired cutting relation to the upper, and a spring for raising the cutter, said cutter sleeve having a portion adapted to be engaged by a driver to impel the cutter through the upper.

20 10. In mechanism for use in shaping shoe uppers, the combination with means for gathering and working inwardly over the bottom of a shoe form the margin of that portion of an upper which extends round the end of the form and for holding the margin of the upper in position to permit its surplus edge portion to be trimmed off, of trimming means comprising co-operating 25 members constructed and arranged to receive between them the edge portion of said margin while it is held by the gathering means and to separate said edge portion from the remainder of the upper stock by 30 a cut extending lengthwise of the edge.

11. In mechanism for use in shaping shoe uppers, the combination with means for gathering and working inwardly over the bottom of a shoe form the margin of that 45 portion of an upper which extends round the end of the form and for holding the margin of the upper in position to permit its surplus edge portion to be trimmed off, of trimming means constructed and arranged for 50 operative movement independently of said gathering means while the margin of the upper is held by the gathering means to trim the edge portion of the upper by a cut extending continuously along the margin 55 from one side to the other of the gathered material.

12. In mechanism for use in shaping shoe uppers, the combination with means for gathering and bending inwardly over the 60 bottom of a shoe form the margin of that portion of an upper which extends round the end of the form and for holding the margin of the upper in its inwardly projecting condition, of trimming means comprising a 65 movable cutter and a positioning device con-

structed and arranged to position the cutter in such relation to the shoe while the upper is held by said gathering means as to render the cutter effective to trim off the entire surplus edge portion of the inwardly projecting 70 margin of the upper round the end of the shoe by movement in a direction transverse to the plane of the shoe bottom.

13. In means for removing surplus upper stock from the toes of shoes, the combination of a plate adapted to extend under the overwiped upper at the toe of a shoe, a cutter movable toward and from said plate to trim off surplus upper, and means to support the shoe against the impact of the cutter.

14. In means for removing surplus upper stock from the toes of shoes, the combination of a stem having a lower end adapted to engage the toe portion of an insole, a cutter movable along said stem toward the insole 85 and constructed to trim off at one operation the entire surplus margin of the upper to be removed at the toe end of the shoe, said cutter and stem being relatively spaced to receive between them at the end of the cutting 90 operation the surplus upper material trimmed off, and a sleeve encircling said stem to be grasped by the operator's hand in placing the cutter.

15. In means for removing surplus upper stock from the ends of shoes, a cutting member arranged to be sustained above the marginal portion of a shoe upper held to the marginal end portion of a shoe sole and mounted for movement toward said sole to 100 sever surplus upper stock, said cutting member being formed to cut off surplus upper stock inwardly of the line along which said stock is held to the sole and along a curved line approximating the contour of the adjacent edge of the sole.

16. In means for removing surplus upper stock from the ends of shoes, the combination of a base member adapted for insertion between the end portion of a shoe sole and the overlying portion of an upper held to the margin of said end of the sole, and a co-operating cutting member arranged to be sustained above said overlying portion of the upper and said base member and mounted for movement toward said overlying portion and base member to sever surplus upper stock, said cutting member being formed to cut off surplus upper stock along a curved line approximating the contour of the adjacent edge of the shoe sole.

17. In mechanism for use in shaping shoe uppers, the combination with end embracing wipers for gathering and wiping inwardly over the bottom of a shoe form the margin 125 of that portion of an upper which extends round the end of the form, of trimming means constructed and arranged to be positioned at the rear of the toe end of the shoe beyond the inner edges of said wipers while 130

the wipers hold the upper in overwiped condition and to trim off the projecting edge portion of the margin of the upper by a cut extending round the end of the shoe from 5 one side to the other.

18. In upper trimming means, the combination of a cutter adapted to be positioned manually lengthwise of a shoe and having a cutting edge adapted to trim off the 10 marginal edge of a shoe upper by a cut extending continuously round the end of the shoe from one side to the other while the margin of the upper is held in overlaid position on the shoe bottom, and means for engaging the 15 insole of the shoe to position said cutter relatively to the edge of the upper.

19. In upper trimming means, the combination of a cutter having a cutting edge adapted to trim off the marginal edge of a 20 shoe upper by a continuous cut extending round the end of the shoe from one side to the other while the margin of the upper is held in overlaid position on the shoe bottom, and means constructed and arranged 25 to project between the insole of the shoe and the overlaid margin of the upper and to position the cutter for operative movement in a direction transverse to the plane of the insole.

20. In means for removing surplus upper stock from the ends of shoes, the combination of an upper trimming cutter, a sleeve arranged to be grasped by the hand of the operator to control the operation of the cutter, and a stem extending lengthwise with- 35

in said sleeve with one end having an outwardly projecting flange constructed for engagement with the insole of the shoe under the margin of the upper to position the cutter relatively to the stock to be trimmed. 40

21. In mechanism for removing the surplus margin of an upper held in gathered position by end embracing wipers, a cutter having a cutting edge adapted to extend continuously along the gathered margin of the 45 upper from one side portion of the shoe bottom to the other side portion and to sever the entire surplus margin of the upper at the end of the shoe at one operation, and a support for said cutter arranged to extend beneath the edge of the upper and manually movable to permit the cutter to be positioned inside of the inner edges of the wipers preparatory to the cutting operation.

22. In mechanism for removing the surplus margin of an upper at the end of a shoe, a cutter and a co-operating shear member constructed and arranged to receive between them the margin of an upper overlying the bottom of a shoe form, said cutter and shear 50 member having co-operating edges arranged to extend continuously along the margin of the upper round the end of the shoe from one side portion of the shoe bottom to the other side portion and to sever the entire surplus 55 margin of the upper at the end of the shoe at one operation.

In testimony whereof I have signed my name to this specification.

MATTHIAS BROCK.
